UNITED STATES PATENT OFFICE.

THOMAS JOSEPH STURTEVANT, OF WELLESLEY, MASSACHUSETTS, ASSIGNOR TO
STURTEVANT MILL COMPANY, A CORPORATION OF MAINE.

ROTARY-BEATER MILL.

1,215,075.

Specification of Letters Patent. Patented Feb. 6, 1917.

Application filed March 16, 1916. Serial No. 84,503.

To all whom it may concern:

Be it known that I, THOMAS J. STURTEVANT, a citizen of the United States, residing at Wellesley, in the county of Norfolk and 5 State of Massachusetts, have invented or discovered certain new and useful Improvements in Rotary-Beater Mills, of which the following is a specification, reference being had therein to the accompanying drawings.

10 This invention relates to that class of crushing mills employing rotary swinging hammers or beaters which are carried by heads attached to rotary shafts, and which rotary hammers or beaters may have pivotal 15 connections with said heads so that they are free to swing, more or less, independently of the shafts, as the latter are rotated carrying the hammers or beaters around with them. These rotary hammers or beaters coöperate 20 with linings with which the mill casings are provided, and as the efficiency of this style of mill is due largely to the closeness with which the hammers or beaters run to the linings or interior casing parts it is desirable to 25 provide for adjustments of the rotary hammers or beaters relative to the linings or inside casing parts, so as to compensate for wear. In machines of this kind it has been customary to provide for the adjustments of 30 the rotary hammers or beaters, relative to the heads or parts by which they are carried, either by radial adjustments of the pivot pins on which the rotary hammers or beaters are mounted, or by providing the heads with 35 differently located holes in which the pivot pins can be mounted at varying distances from the centers of rotation of the shafts. The present invention has for its object to provide for a more convenient and efficient 40 adjustment of the rotary hammers or beaters relative to the linings or inside casing parts; for the purpose of compensating for wear or for varying the output of the mills, as is sometimes desirable with dif- 45 ferent kinds of material being reduced. This object is effected, in accordance with the present invention, by providing for relative adjustments of the rotary hammers or beaters and casing parts by an endwise or 50 longitudinal movement of one or the other of these parts, as will hereinafter more fully appear, instead of by radial adjustments of the hammers or beaters, as has heretofore been done.

55 In the accompanying drawings Figure 1 is

a vertical longitudinal section of a horizontal style of rotary beater mill embodying the present invention. Figs. 2 and 3 are end views of the same, looking from the right and left, respectively, of Fig. 1. Fig. 4 is a transverse section of the same, on line 4—4, 60 of Fig. 1. Figs. 5 and 6 are detail views of a preferred form of liner for the mill casing. Fig. 7 is an elevation of a vertical style of 65 rotary beater mill embodying the present invention, Fig. 8 is a central vertical section of the same on line 8—8, Fig. 7, Fig. 9 is a plan view of the mill shown in Figs. 7 and 8, and Fig. 10 shows a modified form of vertical mill embodying the present invention. 70

Referring to Figs. 1 to 6 of the drawings, illustrating the horizontal style of mill embodying the present invention, 12 denotes the frame or standard portion of the mill which is provided with bearings for the rotary 75 shaft 13 provided with a suitable driving pulley 14. The frame or standard portion 12 of the mill is formed partly hollow affording a mill chamber, and bolted to the said frame portion or standard is an upper cas- 80 ing, affording the upper portion of the mill chamber, said upper casing comprising parts 15, 16 and 17. The mill chamber in its preferred form comprises a cylindrical portion partially formed by the casing part 16, and 85 a conical portion partly formed by the casing part 17. Attached to the rotary shaft 13 are heads 18 in which are mounted pivot pins or bars 19 carrying circular sets of rotary swinging hammers or beaters 20 and 21, any 90 desired number of which may be employed. The rotary beaters 20 are of a straight form, that is to say they have outer faces which are straight, or approximately so, while the outer faces of the rotary beaters 21 are 95 formed tapered or outwardly flaring affording inclined faces to coöperate with the linings of the conical portion of the mill chamber. The cylindrical portion of the mill chamber is preferably provided with spiral 100 or inclined corrugated liners 22 acting as stationary grinding elements, in coöperation with the swinging hammers or beaters, and which will serve to increase or retard the feed or longitudinal movement of the material being reduced according to the direction of rotation of the shaft 13 or the deflection to the right or left of the corrugations as the said material moves from the cylindri- 105 cal portion of the chamber into which it is 110

fed from the hopper 23, at or near one end of the mill casing, to the conical portion of the chamber from which it is finally discharged at the spout 24 located at or near the 5 other end of the mill casing.

The inclined working faces of the rotary beaters 21 in the conical portions of the mill chamber and the inclined corrugated liners 25 coöperating therewith, are preferably 10 formed in steps, so that an endwise adjustment of the shaft 13, with which the beaters are connected, will move certain portions of the working faces of the beaters nearer to or farther from certain coöperating portions 15 of the liners, as will be readily understood from Fig. 1. This endwise adjustment of the shaft 13 is effected by means of an adjusting screw 26 mounted in a portion 12^a of the frame, said adjusting screw having a 20 swiveled coupling connection 27 with the shaft 13. The said screw may be adjusted endwise by means of nuts mounted thereon on opposite sides of the frame portion 12^a, said nuts being provided with hand wheels 25 28 for the purpose of turning the said nuts in adjusting the screw and in locking the screw in any desired position when adjusted.

From the foregoing it will be apparent that an endwise or longitudinal adjustment 30 of the shaft 13, with which the rotary swinging hammers or beaters are connected, will vary the positions of the beaters 21 relative to the liners 22 with which they coöperate, for the purpose of taking up wear or for 35 varying the fineness of the output of the material being crushed.

It will be noted that the material to be crushed is entered into the cylindrical portion of the mill through the hopper 23, and 40 passes from said cylindrical portion to the conical portion thereof, so that as the material is reduced it is subjected to an increased striking speed of the rotary hammers or beaters 21, the portions of which, farthest 45 from the shaft 13, have increased speed due to the progressively increasing diameter of the circle swept by the working portions of these beaters or hammers, thus contributing to a very high efficiency in the operation of 50 the mill. In other words, these beaters or hammers 21 having inclined working faces, are of such construction that different parts 55 of their free ends work in circles of different radii.

55 Referring to Figs. 7, 8 and 9, which illustrate the present invention embodied in a vertical form of crushing mill, 30 denotes a base from which rises standards 31 which support the bottom portion 32 of the mill 60 casing. The body of the casing comprises two similar upright members or halves which collectively form a conical casing portion 17 and a cylindrical casing portion 16, said members being bolted to each other and 65 to the bottom portion 32 and top 45. The

upright casing members are further connected with each other by means of a vertical pivot post 33 which passes through ears 34 and arms 36 projecting from said members. This affords what may be called an 70 "open door" construction, in that either of the upright casing members may be unbolted from the other and from the bottom 32 and top 45 and swung horizontally about the post 33 as a pivot and upon the other casing 75 member as a support, thereby affording convenient access to the interior of the mill when necessary. In the vertical mill construction herein shown the feed opening or hopper 23, which is at the upper end of the mill casing, and which communicates with the cylindrical part of the mill chamber, is formed on one of the swinging parts of the mill casing, while the discharge opening 24 is formed on the bottom portion 32 and is preferably 80 located on the opposite side of the mill casing from said hopper.

The upright rotary shaft 37 is stepped in a bearing box 38 supported by a lever 39 pivoted at one end to the base 30, the other end of said lever being connected with an adjusting screw 40 encircled by a nut 41 bearing on the base 30 and provided with a hand wheel 42 which may be turned for the purpose of adjusting the said shaft 37 vertically. The shaft 37 is provided, as usual, with a driving pulley 43, and has a bearing at its upper end in a sleeve 44 supported at the top of the mill casing. Splined to said shaft 37 are heads 18 in the flanges of which are mounted pivot-pins 19 on which the rotary hammers or beaters 20 and 21 are in turn mounted so that they are free to swing on these pivot-pins as they are carried around with the rotary heads splined to the shaft 37. Coöperating with the rotary hammers or beaters 20 and 21 are corrugated liners 22^a and 25^a, the latter being inclined so as to coöperate with the inclined working faces of the rotary beaters or hammers 21. 105

Fig. 10 shows another form of vertical mill embodying the present invention. In this form of mill most of the parts are similar to those of the style of mill shown in Fig. 8 and are similarly designated by reference numerals. The casing of this mill, however, is of double conical form affording a double conical mill chamber. The upper part of the casing and the swinging hammers or beaters 21 coöperating therewith are similar to those in the lower part of the mill shown in Fig. 8, and the head 18 carrying these swinging hammers or beaters 21 is fixed to the shaft 37 so as to be adjustable vertically therewith. The swinging hammers or beaters 21^a, working in the lower conical part 17^a of the mill casing, are, however, carried by a head 18^a which is splined to the shaft 37 so as to rotate therewith, but which is adjustable independently of said 115 120 125 130

shaft by means of the lever 39^a, supporting said head 18^a, said lever being adjustable by means similar to those by which the lever 39, supporting the shaft 37, is adjustable. The head 18^a rests on a plate 45 which, in turn, rests on ball bearings 46 in a box 47 attached to the adjusting lever 39^a, this construction enabling the head 18^a to rotate freely independently of the lever 39^a by which it is supported.

From the foregoing it will be apparent that by turning the nut 41 by the hand wheel 42 the shaft 37 and the rotary hammers or beaters connected therewith may be adjusted vertically for the purpose of taking up wear or varying the distance between the inclined outer faces of the rotary hammers or beaters 21 and the inclined corrugated linings with which they coöperate.

It will thus be seen that a variation of the distance between the working faces of the rotary beaters or hammers and the corrugated linings with which they coöperate is effected by what may be termed a longitudinal adjustment, or an adjustment in the line of the axis of the shaft carrying the rotary beaters or hammers. This is in contradistinction to the radial adjustments of the rotary hammers or beaters heretofore provided, and these longitudinal adjustments may be much more easily effected than the radial adjustments provided for by prior constructions, and by simpler means. The invention is, however, not to be considered as being limited to the details herein shown, or to the particular means by which these longitudinal adjustments may be effected. For example, instead of adjusting the rotary hammers or beaters longitudinally relative to the casings or liners, such adjustment might be effected by a reversal of this construction whereby the casings or liners would be made adjustable relative to the beaters. Also the longitudinal adjustment might be effected in other ways than by shifting the shaft with which the rotary hammers or beaters are connected, as by shifting the heads longitudinally on the shaft, as shown in Fig. 10, or by shifting the hammers or beaters longitudinally on the heads; or, less preferably, from a mechanical standpoint, by shifting the casing longitudinally relative to the hammers or beaters, as just above stated.

While a conical form of casing is preferred to coöperate with the adjustable beaters in varying the distance between the working faces of the beaters or liners of the casing, it will be understood that different forms of casings might be employed, for the purpose of taking up wear of the beaters, in shifting the latter longitudinally.

The preferred construction herein shown and described affords a mill in which the

reducing chamber is partly cylindrical and partly conical, so as to be outwardly flaring toward its discharge end, and this construction provides a mill of great efficiency and which is not liable to be choked or clogged by feeding in the material too fast, in that the discharge spout 24, in either the horizontal or vertical form of the mill herein shown, affords a free delivery from the flaring reducing chamber, so that the material delivered to the mill chamber from the hopper 23 can pass freely through the mill as it is reduced, and the liability of clogging, which frequently occurs in the operation of rotary beater mills provided with grate bars, is entirely avoided in this improved style of mill.

It will be observed that the means herein shown for adjusting the rotary beaters is such as to permit the adjustment of these parts even when the mill is in operation.

Having thus described my invention I claim and desire to secure by Letters Patent:—

1. In a crushing mill, the combination with a rotary shaft and pivoted swinging beaters connected therewith and having inclined outer or working faces, of a casing part affording a reducing chamber, corrugated liners within said casing part and having inclined faces formed in steps, and means, located outside of the mill casing, for adjusting the said beaters longitudinally of said chamber for the purpose of varying the space between said beaters and liners. 100

2. In a crushing mill, the combination with a rotary shaft and pivoted swinging hammers or beaters connected therewith and the outer ends or faces of which are inclined relative to the axis of said shaft, of casing parts affording a mill chamber, co-operating stationary corrugated liners also inclined relative to the axis of said shaft, and means for adjusting said shaft longitudinally of said chamber while the mill is running, for the purpose of taking up wear or varying the distance between the outer working ends or faces of said hammers or beaters and said liners. 113

3. In a rotary beater mill, the combination with a mill casing and a rotary shaft, of pivoted swinging hammers or beaters carried thereby, the working ends or faces of said hammers or beaters being inclined relative to the axis of said shaft, corrugated liners in said casing and also inclined relative to the axis of said shaft, a flaring casing increasing in diameter toward the outlet part of the mill and the working faces of said beaters increasing in distance from said shaft toward the outlet part of the mill. 125

4. In a rotary beater mill, the combination with a rotary shaft and two sets of pivoted swinging hammers or beaters carried thereby, a casing part, forming the mill 130

- chamber, having cylindrical and conical portions, said conical portion flaring toward the outlet part of the mill, one set of said hammers or beaters working in said cylindrical portion and the other set of said hammers or beaters working in said conical portion, the last-named hammers or beaters having inclined faces flaring outward from said shaft toward the outlet part of the mill.
5. A rotary beater pulverizing mill having a casing providing a reducing chamber which is partly cylindrical and partly conical, a set of pivoted beaters working in each of said casing parts, the cylindrical part of 15 said casing being provided with a hopper or feed opening, and the conical portion of said casing having a discharge opening at its largest part.
6. A rotary beater mill having a casing 20 providing a reducing chamber which is partly cylindrical and partly conical, the cylindrical part of said casing being provided with a hopper or feed opening, and the conical portion of said casing having a discharge opening at its 25 largest end, combined with a rotary shaft within said casing, a set of pivoted hammers or beaters rotating with said shaft in each of the casing parts, and mechanical means to cause the material 30 in process of reduction to have a general longitudinal movement within said casing between said hopper or feed opening and said discharge opening.
7. In a rotary beater mill, the combination 35 with a suitable casing, hinged or pivoted hammers or beaters mounted to rotate within the same and having inclined outer ends or faces, a shaft by which said beaters are carried, and corrugated liners with- 40 in said casing and having faces which are inclined to correspond to the inclined working ends or faces of said beaters, the corrugations of said liners being inclined relative to the said shaft in the direction 45 of the rotation of said shaft, to cause the material being reduced to have a general longitudinal movement in the chamber of the mill.
8. In a rotary beater mill, the combina- 50 tion with a mill casing having a conical por- tion flaring toward its discharge end and provided with liners formed in steps, of a circular series of hinged or pivoted rotary hammers or beaters having inclined work- 55 ing faces also formed in steps and increasing in radial extent toward the said dis- charge end of said casing.
9. A vertical rotary beater mill comprising an upright shaft, pivotally mounted 60 swinging hammers or beaters connected with said shaft to rotate therewith, and a casing affording a mill chamber within which the said swinging hammers or beaters work, said casing increasing in diameter 65 toward its bottom or discharge end, and said hammers or beaters increasing in radial extent toward said bottom or discharge end.
10. A vertical rotary beater mill comprising an upright shaft, pivotally mounted swinging hammers or beaters connected with said shaft to rotate therewith, and a casing affording a mill chamber within which the said swinging hammers or beaters work, said casing increasing in diameter toward its bottom and being provided at or near its top with a feed opening, and at or near its bottom with a discharge opening, and said hammers or beaters increasing in radial extent downward.
11. In a crushing mill, the combination 80 with a circular casing, of a rotary shaft axially disposed in said casing, pivotally mounted yielding hammers or beaters connected to said shaft to rotate therewith, liners in said casing serving, in cooperation 85 with said hammers or beaters, as stationary crushing elements, and closely adjacent to which the working faces of said hammers or beaters run, and means for varying the relative positions of the working faces 90 of said hammers or beaters and said liners.
12. In a crushing mill, the combination 95 with a circular casing a portion of which is conical, of a rotary shaft axially disposed in said casing, pivotally mounted yielding hammers or beaters connected to said shaft to rotate therewith and having inclined working faces, liners in said casing serving, in cooperation with said hammers or beaters, as stationary crushing elements, and closely 100 adjacent to which the working faces of said hammers or beaters run, and means for varying the relative positions of the working faces of said hammers or beaters and said liners.
13. In a crushing mill, the combination 110 with a vertical circular casing a portion of which is conical, of a vertical rotary shaft axially disposed in said casing, pivotally mounted yielding hammers or beaters connected to said shaft to rotate therewith and having inclined working faces, liners in said casing serving, in cooperation with said hammers or beaters, as stationary crushing elements, and closely adjacent to which the 115 working faces of said hammers or beaters run, and means for adjusting said shaft vertically for the purpose of varying the relative positions of the working faces of said hammers or beaters and said liners.
14. In a rotary beater mill, the combina- 120 tion with a vertical mill casing provided with stationary reducing elements, of a vertical shaft in said casing, and horizontally disposed, pivoted rotary beaters carried by 125 said shaft and between the ends of which beaters and said cooperating stationary elements the material is reduced, said casing being provided at its top at one side with a feed hopper so as to enter the material to 130

be reduced directly between the outer ends of said beaters and said stationary reducing elements.

15. In a rotary beater mill, the combination with a vertical casing having a feed opening at its upper part and a discharge opening at its lower part, of a vertical rotary shaft in said casing, a plurality of sets, in vertical series, of horizontally swinging pivoted beaters connected with said shaft to rotate therewith, and stationary corru-

gated crushing elements coöperating with said horizontally swinging beaters; whereby material to be reduced may be entered at the top of the mill and will be successively subjected to the coöperative action of the several sets of beaters and stationary crushing elements as it passes from the top to the bottom of the mill chamber.

15
In testimony whereof I affix my signature. 20

THOMAS JOSEPH STURTEVANT.
